(57) **CLAIM**

The ornamental design for a canister as shown and described.

DESCRIPTION

FIG. 1 is a top front left-side perspective view of the canister, according to the new design.

FIG. 2 is a bottom front left-side perspective view of the canister shown in FIG. 1.

FIG. 3 is a top front right-side perspective view of the canister shown in FIG. 1.

FIG. 4 is a bottom front right-side perspective view of the canister shown in FIG. 1.

FIG. 5 is a left side elevation view of the canister shown in FIG. 1.

FIG. 6 is a right side elevation view of the canister shown in FIG. 1.

FIG. 7 is a rear elevation view of the canister shown in FIG. 1.

FIG. 8 is a front elevation view of the canister shown in FIG. 1.

FIG. 9 is a top plan view of the canister shown in FIG. 1; and,

FIG. 10 is a bottom plan view of the canister shown in FIG. 1.

The broken lines in the drawings illustrate portions of the canister that form no part of the claimed design.

1 Claim, 9 Drawing Sheets
